UNITED STATES PATENT OFFICE

172,948

COMBINED MEDICINE AND TOILETRY CABINET

Emanuel Butkiewicz and Robert P. McGurk, Los
Angeles, and Willard J. Johnson, Playa Del Rey,
Calif.

Application August 18, 1953, Serial No. 26,497

Term of patent 14 years

(Cl. D4—3)

To all whom it may concern:

Be it known that we, Emanuel Butkiewicz, a citizen of the United States and resident of Los Angeles, in the county of Los Angeles and State of California; Robert P. McGurk, a citizen of the United States and resident of Los Angeles, in the county of Los Angeles and State of California; and Willard J. Johnson, a citizen of the United States and resident of Playa Del Rey, in the county of Los Angeles and State of California, have invented a new, original, and ornamental Design for a Combined Medicine and Toiletry Cabinet, of which the following is a specification, reference being had to the accompanying drawing, forming a part thereof.

Figure 1 is a perspective view of a combined medicine and toiletry cabinet, showing our new design;

Figure 2 is a front view on a somewhat larger scale; and

Figure 3 is a top plan view.

We claim:

The ornamental design for a combined medicine and toiletry cabinet, substantially as shown.
